CHARLES H. CUNO, OF MERIDEN, CONNECTICUT, ASSIGNOR TO THE CUNO ENGINEERING CORPORATION, OF MERIDEN, CONNECTICUT, A CORPORATION OF CONNECTICUT.

TIMER.

1,188,906.

Specification of Letters Patent. Patented June 27, 1916.

Application filed November 30, 1915. Serial No. 64,347.

To all whom it may concern:

Be it known that I, CHARLES H. CUNO, a citizen of the United States of America, residing at Meriden, Connecticut, have invented a new and useful Timer, of which the following is a specification.

My invention relates to an improved timer construction for electric ignition purposes, said invention aiming at economy of construction, simplicity of parts, and durability and efficiency of operation.

In the accompanying drawing: Figure 1 illustrates my improved timer in end elevation as it would appear in use, part of the same being broken away and in section. Fig. 2 is a section on the plane of the line 2—2, Fig. 1. Fig. 3 is a perspective view of said parts separated.

- 1 represents the back of the timer.
20 2 represents the shaft by which the timer arm is driven in the usual manner from the customary source of power. In this particular instance the timer is adapted to a four cylinder internal combustion engine.
25 3 is a housing concentrically mounted relatively to the shaft 2. In this instance the housing is circular in form and is yieldingly pressed by a spring 4 against the back 1 and is prevented from lateral displacement on the latter by a flange 5. The spring 4 may be mounted at one end in any suitable manner, while its other end may bear in a central depression 6 at the outer end of the housing 3.
30 7, 8, 9, 10 are binding posts which are suitably connected with a corresponding number of the insulated terminals within the housing, each binding post having a terminal corresponding with the terminal 11 shown as connected to the binding post 7 in Fig. 1.
40 12 is a ring of insulating material, the several terminals being carried by said ring 12 and being substantially flush with the inner wall thereof, so that they will be properly and successively engaged by the contact member of a rotary timer arm. The ring 12 is as shown in Fig. 2, spaced away from the outer wall 13 of the housing 3 so as to provide an annular space or reservoir 14 to hold a suitable lubricant.
45 15 is a plug for an oil hole, the same being located in the outer part of the housing 3 so that oil may be squirted into the casing and conducted down into the annular oil reservoir 14.
- 16 is a contact member preferably in the form of a roller suitably designed to roll around the inner surface of the insulating ring 12 for the purpose of successively engaging the terminals 11 carried by the binding posts 7, 8, 9 and 10. This contact member 55 16 in the particular form shown, is mounted in a carrier yoke 17 which is longitudinally slideable relatively to its supporting member. The said supporting member comprises two side arms 18—18, the opposite edges of which project inwardly toward each other and are so spaced as to afford an effective guideway or channel for the contact carrier yoke 17. The arms 18—18 are connected at their rear ends by the bridge 19 60 70 which is preferably integral therewith.
20—20 are ears at the opposite ends of the connecting bridge 19, which ears have guide passages.
21—21 are corresponding ears at the opposite ends of the base of the carrier yoke 17.
22—22 are guide pins secured to the ears 21—21 and pass down through the guide passages in the ears 20—20. The ends of these pins 22 may be headed to prevent said pins 80 from being withdrawn from the guide passages in the ears 20—20.
23—23 are coil springs surrounding the guide pins 22—22 and exerting pressure between the ears 20—21. I have found that a 85 coil spring is preferable for the purpose of pressing the contact carrier yoke 17 outwardly, because it possesses the greatest durability. The yoke 17 and the supporting and guiding member therefor, may be struck 90 up from sheet metal and, therefore, produced with great speed, economy and uniformity. When these parts are assembled they are mounted on that part of the shaft 2 which projects into the housing 3 so as to 95 stand substantially as shown in Figs. 1 and 2.
24 is a pin which is designed to pass through the outer end of the shaft 2 and which may have a right angle arm 24^a to 100 perform the function of a key. The parts 18—18 have passages therein of a size and shape to permit the same to be slipped over the shaft when the key is in place, said key holding said parts from independent rotation on the shaft when the parts are assembled.
25 is a nut designed to be screwed on to

the outer end of the shaft 2, to hold the timer arm in the position shown in Fig. 2.

26 is a spring washer which may be provided between the nut 25 and the adjacent side of the timer arm.

In operation the parts would be assembled as shown in Figs. 1 and 2 wherein the movable contact roller 16 is located within the insulating ring 12 and is pressed against the same with the proper degree of tension by the springs 23—23. Thus when the shaft 2 is rotated, the roller 16 will successively traverse the contacts 11 so as to close the circuit intermittently and successively through the several binding post terminals. The spring pressure of the contact roller 16 against the inner wall of the ring 12 and the contacts 11 is in a radial direction. So far as it is necessary for the contact roller 16 to yield, this yielding action is permitted without danger of binding by reason of the fact that a long bearing is provided for the roller carrying element, the bearing points occurring at the opposite edges of the yoke 17 at one side of the shaft 2 and by the guide pins 22 in the ears 20 at the opposite side of the shaft. I have found that by causing the roller 16 to exert a radial pressure against the inner wall of the ring, all tendency of bobbing, such as is likely to occur in the old type of movable contact support is avoided. Again, by providing springs of the type shown herein I am enabled to secure a more even pressure of the movable contact against the surrounding ring.

It will be understood I have shown the timer in this instance so constructed that the frame constitutes the ground or one end of the circuit, while the binding posts 7, 8, 9 and 10 carrying the respective terminals are insulated and constitute the other end of the circuit. The guide pins 22 serve not only to hold the parts 17 and 18—18 in co-operative relation so that they will collectively constitute a timer arm, but said guide pins also serve to steady the coil springs 23, and to prevent them from buckling. The housing 3 may be oscillated on the back 1 to the desired degree for the purpose of "advancing" or "retarding" the time of ignition, and for this purpose an operating arm 27 may be provided. In operation, the lubrication of the various parts is maintained by reason of the fact that the roller 16 will pick up and distribute the lubricant contained in the reservoir 14.

It is obvious that in various respects I may modify the design of the various parts illustrated and described without departing from the spirit and scope of my invention.

The member which carries the rotatable contact is in effect an extensible arm, and the piece 17 which directly carries the roller contact is not only in yoke form, but the piece made up of the two side arms 18—18

and the bridge 19 is also in effect a yoke. These yokes only partially overlap, and hence, the importance and value of the supplementary guiding means, which affords a long bearing and thus prevents the wedging or jamming of said parts which might otherwise occur with a short overlap.

What I claim is:

1. In a timer, a ring of insulating material, a contact terminal at the inner edge thereof, a rotatable element concentrically mounted relatively to said ring, a longitudinally extensible arm carried by said rotatable element and projecting radially therefrom and comprising two telescopic members, a rotatable contact terminal carried by the outer part of said arm and arranged to traverse the interior of said ring and the terminal carried thereby, two guide pins secured to the outer part of said extensible arm and slidably connected with the other part of said extensible arm, and two coil springs surrounding said guide pins and exerting pressure against said parts in a direction to extend said arm.

2. In a timer, a rotatable contact carrying arm comprising two telescopic members, the outer one of said members being in the form of a yoke open at the outer end and arranged to carry a rotatable contact roller, the other part of said arm comprising two spaced side pieces, a guide channel between them for receiving the rear end of said yoke, two guide pins carried by the yoke and slidably connected with the other part of said arm to the rear of the yoke to assist in the guiding of said yoke as it is reciprocated, and a spring for exerting an outward radial pressure against the yoke.

3. In a timer, a rotatable contact carrying arm comprising two telescopic members, the outer one of said members being in the form of a yoke open at the outer end and arranged to carry a rotatable contact roller, the other part of said arm comprising two spaced side pieces, a guide channel between them for receiving the rear end of said yoke, two guide pins carried by the yoke and slidably connected with the other part of said arm to the rear of the yoke to assist in the guiding of said yoke as it is reciprocated, coil springs surrounding said guide pins and exerting pressure against said yoke in an outward direction.

4. In a timer, a timer arm including two extensible members, the outer member comprising a one-piece yoke including two side arms arranged to receive between them a rotatable contact roller, the inner member comprising two channelled side arms integrally united at their rear ends by a bridge, and having channels forming a guide-way for said yoke, two guide pins carried by the rear end of said yoke and slidably connected with, and guided by, the inner member of

said arm, and means for exerting a yielding pressure against said yoke in an outward direction.

5. In a timer, a contact carrying arm comprising two extensible members, the inner member comprising two spaced side arms connected at their rear ends, the outer member also comprising two spaced side arms also connected at their rear ends, said outer member being slidable between the arms of the inner member, a shaft passage through the side arms of the inner member, a guide extension carried by the outer member and slidably connected with the inner member at the rear of said shaft passage therein, and a spring for exerting outward pressure against the outer member of said arm.
6. In a timer, a contact carrying arm comprising two extensible members, the inner member comprising two spaced side arms connected at their rear ends, the outer member also comprising two spaced side arms also connected at their rear ends, said outer member being slidable between the arms of the inner member, a shaft passage through the side arms of the inner member, a guide extension carried by the outer member and slidably connected with the inner member at the rear of said shaft passage therein, and a spring for exerting outward pressure against the outer member of said arm, said spring being supported by said guide extension.

7. In a timer, a relatively stationary contact terminal, a relatively movable contact arranged to traverse the same, a rotatable shaft, said extensible arm being carried by said shaft and comprising two partially overlapping members, one of said members being guided on the other and a supplementary guiding means between said two partially overlapping members.

8. In a timer, a relatively stationary contact terminal, a relatively movable contact arranged to traverse the same, a rotatable shaft, said extensible arm being carried by said shaft and comprising two partially overlapping members, one of said members being guided on the other and a supplementary guiding means between said two partially overlapping members, said partially overlapping members being of yoke formation with the open ends of said yokes facing in the same direction.

55. 9. In a timer, a stationary back, a shaft projecting therethrough and mounted to rotate, a contact terminal carried thereby and means for connecting said contact terminal thereto comprising two parallel arms directly carried by the said shaft and formed with guide-ways and two parallel arms slidable in said guide-ways at one side of said shaft, said contact comprising a roller revolvably mounted between the last two mentioned arms, means for forcing said last

two mentioned arms outwardly in said guide-ways relatively to said shaft, a relatively stationary housing mounted on said body and adjustable relatively thereto and a contact carried thereby for coöperation with the contact carried by the shaft, one of said contacts being insulated from its support.

10. In a timer, a stationary back, a shaft projecting therethrough and mounted to rotate, a contact terminal carried thereby and means for connecting said contact terminal thereto comprising two parallel arms directly carried by the said shaft and formed with guide-ways, two parallel arms slidable in said guide-ways at one side of said shaft, a contact comprising a roller revolvably mounted between the last two mentioned arms, means for forcing said last two mentioned arms outwardly in said guide-ways relatively to said shaft, a relatively stationary housing mounted on said body and adjustable relatively thereto and a contact carried thereby for coöperation with the contact carried by the shaft, one of said contacts being insulated from its support, said insulating means comprising a ring mounted in said housing near one end thereof but spaced therefrom to provide an annular lubricant carrying groove adjacent to one side of said housing.

11. In a timer, a rotatable shaft, a relatively stationary housing for one end of said shaft, a contact carried by said housing, another contact carried by said shaft and arranged to coöperate with the first mentioned contact, means for connecting the second mentioned contact to said shaft comprising two parallel plates having a shaft passage through the same, with means for securing said plates on said shaft against independent rotation, a U-shaped contact supporting device arranged between said plates and the one side of the shaft, said U-shaped device being slidably mounted on said plates with means for yieldingly moving said U-shaped device in the contact engaging direction.

12. In a timer, a rotatable shaft, a pair of parallel plates carried thereby and forming a guide-way between them extending radially from said shaft, a contact carrying element mounted in said guide-way at one side of said shaft, springs on opposite sides of said shaft for moving said contact carrying element in one direction.

13. In a timer, a rotatable shaft, a pair of parallel plates carried thereby and forming a guide-way between them extending radially from said shaft, a contact carrying element mounted in said guide-way at one side of said shaft, springs on opposite sides of said shaft for moving said contact carrying element in one direction, and means for limiting the sliding movement of said con-

tact carrying element relatively to said plates.

14. In a timer, a substantially vertical stationary back, a substantially horizontal 5 rotatable shaft projecting through said back, a housing closed at one end and over-standing one end of said shaft and having an annular wall surrounding said shaft, means on said back for engaging said 10 housing and holding the same concentric relatively to said shaft, said housing being adjustable angularly around and relatively

to said shaft, a ring of insulating material mounted within the annular part of said housing and forming an annular lubricant 15 carrying space between itself and the closed end of said housing, a contact carried by said ring and insulated from said housing, another contact carried by said shaft and arranged to traverse the inner edge of said 20 ring and the contact carried thereby as said shaft is rotated.
